ufacturing Company, Urbana, Ohio, a corpo-
ration of Ohio

Application November 25, 1935, Serial No. 51,404
Renewed March 21, 1938

8 Claims. (Cl. 73—337)

This invention relates to improvements in hygrometers of the type in which the moisture-responsive element is formed of wood or similar fibrous material.

5 An object of the invention is to provide means for compensating for varying degrees of expansion of the moisture-responsive element, particularly when such element is formed of wood.

In the accompanying drawing:

10 Fig. 1 is a front elevation.

Fig. 2 is a vertical section on the line 2—2 of Fig. 1.

Fig. 3 is a front elevation of the device with the front casing removed.

15 Fig. 4 is a fragmentary enlarged horizontal section on the line 4—4 of Fig. 3.

Fig. 5 is a fragmentary enlarged section on the line 5—5 of Fig. 2.

20 Fig. 6 is a view similar to Fig. 5 with the parts in a different working position.

Fig. 7 is also a view similar to Fig. 5 with the parts in a still different working position.

Fig. 8 is a fragmentary enlarged horizontal section on the line 8—8 of Fig. 3.

25 Fig. 9 is a diagram illustrating the improved method of obtaining material for the hygroscopic element.

Fig. 10 is a perspective view showing a further step in the process of making the hygroscopic element.

Fig. 11 is a chart illustrating the effect of moisture vapor on the hygroscopic element.

Referring to the drawing, 1 represents a back plate on which the mechanism is mounted, the 35 mechanism being enclosed by a front cover or casing 2. In the front casing 2 is an opening or window 3, and at 4 is shown a small section of glass supported in the casing 2. To the rear of the window 3 is the scale plate 5, also supported 40 in the casing 2. The graduations 6 on the scale plate will be explained more fully at a later point in the description.

45 There is provided a needle 7 which sweeps over the graduations 6 on the scale plate 5. The needle 7 is fixed on the outer end of a sleeve 8 which is revolvably supported on a stud 9 secured to the back plate 1, the relation of the circularly disposed graduations 6 and stud 9 being concentric.

50 The sleeve 8 is given a partial rotation in a clock-wise direction by the actuation of the hygroscopic element 10 through linkages including a double armed lever 11, a light chain 12 and a peculiarly formed lever 13 which by its formation in conjunction with a portion of the sleeve

8 constitutes a part of the invention as will be explained.

Referring to the hygroscopic element 10, this element is a member formed, in the present instance, of five sections of a wood such as basswood, it being understood that this number of sections is not essential, since for other linkages or scale, an element having a larger or smaller number of sections might be found more suitable. The element is built up of small sections in the 10 manner to be described for the two-fold purpose of obtaining an ample movement of the needle over the scale by the absorption of the moisture of the air by the element and of causing the element to expand in as nearly a straight line as 15 possible.

This is explained as follows: Wood reacts to absorbed moisture by expanding in all directions; that is, a stick of wood will increase in length, breadth and thickness. Its greatest degree of 20 increase, however, is in a direction along the lines of the original tree annulations or tree growth rings, and advantage is taken of this property in making the improved element by so selecting the lumber of which the element is 25 formed that the annulations or growth-rings are substantially in alignment from end to end of the element.

This selection of material is made by taking from the lumber sawed from a log only a few 30 of the boards removed from the outer periphery of the log. Referring to Fig. 9, the log is represented at 14 and the annulations thereof at 15. As can be seen, the saw-cuts 16 by which the first boards are taken from the log as shown on the 35 three sides illustrated are tangential to the annulations 14, and in distinguishing the broader surfaces of a board as the top and bottom surfaces, it will be seen that some few annulations extend from edge to edge and are substantially 40 parallel to the top and bottom surfaces, and if the log is comparatively large in diameter there is little noticeable lack of parallelism in these first boards.

As was stated, the greatest degree of expansion or increase in the dimensions of the board is in the direction of the annulations; therefore, in such boards as are mentioned it is the width that shows the greatest increase. Accordingly, these are the preferred boards, those which would 45 be cut later toward the center having annulations of too short radius.

In expanding, the preferred boards, even of comparatively large radius, tend to bow to an arcuate form due to the annulations, and to cause 50

the element to expand in a straighter line, these preferred boards are ripped into strips of substantially square cross-section, the small squares 17 in Fig. 9 representing the ends of strips as produced by the ripping saw cuts 18. To gain a still further average, strips from several trees are preferred from which to assemble a plank from which elements are cut, as for example, in the laminated plank P, Fig. 10, the several strips 10 A, B, C, D and E are taken from lumber 15 procured by the selective process just described from five different trees of the same species. It should also be explained that in assembling this laminated plank P that it is essential that the annulations of alternate strips curve in the same 20 direction, as strips A, C and E show annulations bowing generally and slightly upward, while in strips B and D, the curves are generally downward, and that all the annulations are in a general alignment from edge to edge of the plank P. These strips are cemented to each other by a water-proof cement in forming this laminated 25 plank.

The hygroscopic elements 10 are cut from the 30 end of the laminated plank, the saw cuts by which they are removed being indicated at 19, Fig. 10, and the dimension that was the "width" of the plank is now the "length" of the detached element. Also, the annulations are in substantially 35 straight alignment from end to end of the element as can be seen in the element 10, Fig. 2, although it should be understood that in each instance all annulations are shown curved to an exaggerated degree for the purposes of explaining the method of manufacturing the element.

It is preferable that the elements should be 40 comparatively thin, referring to the length of the end grain. In absorbing moisture, much of it is taken up in the end grain, and if the end grain is short, as is shown in the present case in Figs. 3 and 8 for the element 10, the time required in responding to a change in the atmosphere is shortened, either from a dryer to a more humid state or vice versa.

In manufacturing a wooden element after the manner described, warping or buckling is eliminated and a short time lag is provided. Another peculiarity of the wooden element will be mentioned and at a later portion of the specification 50 a description is given of the means for compensating for this peculiarity.

The mounting of the element 10 on the back plate 2 consists of a metallic strip 20 riveted by rivets 21 to the back plate 2. At the upper and 55 lower ends of the strip 20 the end portions are outwardly turned (Figs. 2 and 3) to form parallel arms 22 and 23. Through aligned openings in the arms 22 and 23 two parallel rods 24 are passed. These rods are guides for the element 60 10, as in the edges of the element 10 are lengthwise grooves 25 slightly larger than the rods 24. These grooves are clearly indicated in the enlarged sectional view Fig. 8 and are also shown in the end element in Fig. 10 in broken lines. 65 Incidentally, the grooves 25 serve to provide very short end grain at these portions of the element.

The wooden element rests on an adjustably fixed plate 26 (Figs. 2 and 3) slidably disposed in relation to the guide rods and supported on 70 a small set screw 27 threaded in the arm 23. The purpose of this adjustment will also appear later.

Any expansion or contraction of the element due to atmospheric humidity changes is communicated to the needle 1 by the previously men-

tioned double armed lever 11, chain 12 and lever 13. In the double armed lever 11 there is a shorter arm 11' and a longer arm 11''. This lever 11 is pivotally mounted on the stud 28 in such position that the shorter arm 11' of the lever 11 rests on the upper end of the element, there being interposed between the element and the end of the short lever 11' a small wear plate 29 slidably mounted on the guide rods.

The other longer arm 11'' of this lever 11 consists of a sheet metal member 11a having a sheave-like groove formed in its outer edge which is concentric to the stud 28 on which the lever 11 is pivoted. At the lower end of the groove 30 a very light chain 12, here shown considerably 15 exaggerated as to size, is connected, a chain being preferred because, being of a material not susceptible to humidity changes, only the changing 20 of the element itself is communicated to the needle. The upper end of the chain 12 is connected to the lever 13 secured to the previously mentioned sleeve 8 to which the needle 1 is attached.

As before stated, the lever 13 is peculiarly 25 formed in order to compensate for a peculiarity in the manner in which the wooden element expands on absorption of moisture, the peculiarity being that an increase is slight up to a condition represented by a figure such as 65% relative humidity, but thereafter to the highest figure the 30 increase is much greater. This peculiarity is illustrated by the graph shown in Fig. 11. Referring to this figure, expansion is plotted against 35 percentages of relative humidity, whereby the rate of expansion is shown. As to the curve indicated 40 at 31, this curve has an indefinite origin near the point represented by 10% relative humidity since little is known of conditions below this percentage, and has an indefinite ending near the 100% relative humidity portion, as this condition seldom occurs, but it will be noticed that from the origin to approximately 65% relative 45 humidity, the curve 31 is fairly uniform in its rise. From 65% to approximately 95% relative humidity, the rise is much more abrupt, and the 50 proportional rise due to changes in humidity conditions is shown by the dimensions E and E' on the expansion side of the chart, thereby showing that the rise E' for a change of from 65% to 95% relative humidity (30% only) is nearly twice the 55 rise E from 10% to 65%, which represents an increase of 55%, nearly twice the increase of 30% just mentioned.

This means that if compensating devices were 60 not employed the graduations 6 on the scale plate 55 5 could not be equally spaced as is preferred for easy reading, it being noticed that the graduations 6 of the present invention extend over a half circle and are divided into ten equal spaces, the indicia 0 to 100 being read in percentages 65 of relative humidity.

The lever 13 is secured to the rear end of the sleeve and the chain 12 is hooked to its outer or free end, the chain crossing over to the right (Fig. 3) from its connection on the left to the 70 lever 11 and passing to the right of the pivotal center of the needle 1 as represented by the stud 9. Therefore, by an expansion of the element 10 the increase in length results in an upward movement of the shorter arm 11', a downward movement of the longer arm 11'' and a downward pull on the chain 12 which causes a partial rotation of the needle to the right (Fig. 1).

For transmitting an expansion in length of the

element from a low figure to approximately 60% on the scale, which represents, as stated before, a small increase in the length of the element for a considerable change in atmospheric conditions it is necessary to provide, in effect, that the radius at which the upper end of the chain is connected to the sleeve 8 should be proportionately small as compared to the longer lever arm 11''. This is accomplished in the present invention by causing the run of the chain to bear against a portion of the sleeve 8 which is machined at this point to provide the suitable radius. This portion of the sleeve 8 is the groove 32 (Figs. 2 and 4) and the depth of the groove is such that the chain makes contact with sides of the groove at the proper radius.

This feature is partially shown in Fig. 5, wherein it can be seen that if the lever 13 were to be moved from the left to its present vertical position that, regardless of the point or radius at which the chain 12 is actually connected to the lever 13, the effect is similar to a chain and sprocket system, the movement of the needle being uniformly proportional to the increase in length of the element 10 so long as the run of the chain bears against the bottom of the groove 32.

A further increase in atmospheric humidity causes the element to increase in length at a more rapid rate and to slow down the needle movement it is necessary to provide an effect similar to placing the chain on a sprocket of larger diameter. This is provided for by so placing a finger 33 extending outwardly from the right edge of the lever 13 that the run of the chain in bearing against the finger is the same as described in connection with the groove 32; that is, when the chain leaves the groove 32 or the radius represented thereby, and so long as the chain bears against the finger, up to the point where it leaves the finger (Fig. 6), the needle movement is over a shorter range. This range on the scale extends from approximately 60% to 75% relative humidity.

For percentages above the latter figure, the needle must be still further slowed down which is done by passing the chain over the bent-over extreme outer free end 13' of the lever 13. It should also be explained that no error is introduced by an unsuitable method of connecting the lower end of the chain to the lever 11. As before stated, there is provided a plate 11a attached to the lever 11, forming the longer lever arm 11''. The partial periphery of the plate 11a is grooved, the groove being concentrically disposed with reference to the stud 28. In this groove the run of the chain lies, the chain being connected to the plate at the lower end of the groove. Thus, the chain is tangent to the axis of rotation of the lever 11 and the effective radius does not change, and the proportions of this radius with the effective radii as represented by the contact of the chain with the groove 32, the finger 33 or the free end 13' of the lever 13 do not change.

When the degree of humidity decreases, the element 10 gives up its moisture and contracts and becomes shorter. The lever 11 follows this decrease in length due to the effect of the return spring 34 which is hooked at one end to any suitable point on the back plate 2 and also by chain 35 to any suitable point on the lever 13, the chain passing to the left of the center of the needle. Consequently, as the element shrinks, the needle moves to the left.

In assembling the hygrometers, it is preferable

that the elements are of the same approximate length at the same approximate percentage of relative humidity. Accordingly, the plank P (Fig. 10) is slightly wider, and thereby provides slightly longer elements than are needed for any condition of humidity. The elements are then subjected to a controlled humidity condition for a suitable time to insure that they are stationary at that condition, and are then trimmed to a definite length. This means that each time that length is reached, the conditions are the same as the controlled condition. To compensate for any small error in controlling the humidity condition or in trimming the element to length, the small set screw 27 previously mentioned is run up or down, as the case may be.

Having thus described our invention, we claim:

1. In a hygrometer, a moisture-responsive element, a lever operated thereby, an oscillatory sleeve, a pointer carried by said sleeve, a second lever connected with said sleeve, a chain connecting said levers, said chain bearing on said sleeve during a predetermined movement of said pointer from zero to impart a uniform movement to said pointer, said chain thereafter being free from said sleeve, and means on said second lever to cause a slower movement to be imparted to said pointer.

2. In a hygrometer, a moisture-responsive element, a lever operated thereby, an oscillatory member, a pointer carried by said member, a second lever connected with said member, a chain connecting said levers, said chain during a given initial movement of said moisture responsive element passing over a surface on said oscillatory member of given radius with relation to the axis of oscillation of said oscillatory member and during subsequent movement of said moisture-responsive element passing over surfaces on said second lever of increasing effective radii with respect to the axis of oscillation of said member.

3. In a hygrometer, a moisture-responsive element, a lever operated thereby, and an oscillatory member, a second lever connected to said member, a chain connecting said levers, said chain during a given initial movement of said moisture-responsive element passing over a surface on said oscillatory member of given effective radius with relation to the axis of oscillation of said oscillatory member, and a projection on said second lever of greater radius with relation to the axis of oscillation of said oscillatory member over which said chain passes after leaving said surface during the subsequent movement of said moisture-responsive element to decrease the speed of movement of said pointer.

4. In a hygrometer, a moisture-responsive element, a lever operated thereby, and an oscillatory member, a second lever connected to said member, a chain connecting said levers, said chain during a given initial movement of said moisture-responsive element passing over a surface on said oscillatory member of given radius with relation to the axis of oscillation of said oscillatory member, and a projection on said second lever of greater effective radius with relation to the axis of oscillation of said oscillatory member over which said chain passes after leaving said surface during the subsequent movement of said moisture-responsive element to decrease the speed of movement of said pointer, said second lever having a surface of greater effective radius with respect to the axis of oscillation of said oscillatory member than that of said projection over which said chain passes after

leaving said projection to further decrease the speed of movement of said pointer.

5. In a hygrometer, a moisture-responsive element, a lever operated thereby, an oscillatory member, a pointer carried by said member, a second lever connected to said member, a chain connecting said levers, means on said oscillatory member and cooperating with said chain for causing said pointer to move at a substantially constant speed during a predetermined initial expansion of said moisture-responsive element, and means on said second lever and cooperating with said chain and acting during the subsequent expansion of said moisture-responsive element to decrease the rate of movement of said pointer.

6. In a hygrometer, a moisture-responsive element, a lever having a short arm operatively associated with said element and a long arm having a sheave-like groove concentric with the axis of rotation of said lever, an oscillatory member, a second lever connected with said member, a chain connecting said levers and located in said concentric groove, a pointer carried by said oscillatory member and means on said oscillatory member acting upon said chain to cause said pointer to move at a substantially constant speed during a predetermined initial expansion of said moisture-responsive element, and means on said second lever during a subsequent expansion of said moisture-responsive element to decrease the rate of movement of said pointer.

7. In a hygrometer, a moisture-responsive element, a lever operated thereby, an oscillatory

member, a pointer carried by said member, a second lever connected to said member, a chain connecting said levers, means on said oscillatory member and cooperating with said chain for causing said pointer to move at a substantially constant speed during a predetermined initial expansion of said moisture-responsive element, means on said second lever and cooperating with said chain and acting during the subsequent expansion of said moisture-responsive element to decrease the rate of movement of said pointer, and a spring to return the parts when the moisture-responsive element contracts.

8. In a hygrometer, a moisture-responsive element, a lever having a short arm operatively associated with said element and a long arm having a sheave-like groove concentric with the axis of rotation of said lever, an oscillatory member, a second lever connected with said member, a chain connecting said levers and located in said concentric groove, a pointer carried by said oscillatory member, means on said oscillatory member acting upon said chain to cause said pointer to move at a substantially constant speed during a predetermined initial expansion of said moisture-responsive element, means on said lever acting during a subsequent expansion of said moisture-responsive element to decrease the rate of movement of said pointer, and a spring to return the parts when the moisture-responsive element contracts.
